VICTOR E. MEYER, OF HARRISON, NEW JERSEY, ASSIGNOR TO A.
FOLSOM AND SONS, OF BOSTON, MASSACHUSETTS.

Design No. 3,416, dated March 23, 1869.

DESIGN FOR A CARPET-PATTERN.

The Schedule referred to in these Letters Patent and making part of the same.

To all persons to whom these presents may come:

Be it known that I, VICTOR E. MEYER, of Harrison, in the county of Hudson, and State of New Jersey, have invented or produced a "New Ornamental Design for a Pattern for a Floor-Cloth, or for a Carpet," such design to be either printed, or painted, or woven, or otherwise fixed on or in a cloth or other material; and I do hereby declare the same to be represented in the accompanying drawing.

In such drawing, A denotes a square, having each of its corners truncated, whereby it is converted into an octagonal figure, having four sides longer than the

other four. Each side of the figure is composed of a series of umbels, as shown.

Each longer side of the figure is bounded by a triangle, B, ornamented, as represented.

Within the octagonal base, A, is a border, a, ornamented at its corners, and formed as represented; and there is also within said border a bouquet of fuchsias, the whole being as shown in the drawing.

I claim the said design as represented and described.

W. BRADSHAW.
